WINDOW SASH

Herold H. Hebestreit, Mio, Mich.

Application June 17, 1942, Serial No. 447,414

1 Claim. (Cl. 20—56)

The present invention relates to new and useful improvements in window sashes, and has for its primary object to provide, in a manner as hereinafter set forth, a device of this character wherein the usual putty for retaining the lights or glasses in position is dispensed with.

Another very important object of the invention is to provide a window sash of the character described comprising a novel construction and arrangement whereby the glasses may be expeditiously replaced when necessary.

Other objects of the invention are to provide a window sash of the aforementioned character which will be comparatively simple in construction, strong, durable, attractive in appearance, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is an elevational view of a window sash constructed in accordance with the present invention, looking at the inner side thereof.

Figures 2 and 3 are vertical sectional views taken substantially on the lines 2—2 and 3—3, respectively, of Figure 1.

Figure 4 is a view in side elevation, showing the lower mullion before the halves thereof are separated.

Figure 5 is a view in horizontal section, taken substantially on the line 5—5 of Figure 1.

Figure 6 is a detail view in perspective of one of the removable, resilient glass retaining channel members.

Figure 7 is a view in vertical section through a modification.

Referring now to the drawing in detail, it will be seen that the sash comprises top, bottom and side rails 1, 2 and 3, respectively. A removable transom 4 extends between the side rails 3. Extending between the transom 4 and the bottom rail 2 is a removable mullion 5. A mullion 6, which is also removable, extends between the transom 4 and the top rail 1. The members 1 to 6, inclusive, define a plurality of openings for the reception of removable glasses 7.

The opposed inner edges of the members 1 to 6, inclusive, are oppositely and ornamentally beveled, as at 8, and have formed therein grooves or channels 9 for the reception of the marginal portions of the removable glasses 7. Channel members 10 of suitable resilient material are remov-

ably mounted in the grooves 9 on one side of the glasses 7 for holding said glasses firmly in position in said grooves which, it will be observed, are comparatively wide. The resilient channel members 10 are inserted under tension in the grooves 9 between the glasses 7 and the opposed walls of said grooves. As shown to advantage in Figures 2 and 6 of the drawings, the resilient channel members 10 include converging side flanges 11 having external beads 12 on their free longitudinal edges. The beads 12 are adapted to bear on the glasses 7 and the opposed side walls of the grooves 9.

The groove 9 in the bottom rail 2 has formed in its bottom a comparatively narrow extension constituting a pocket or well 13 for the reception of the lower glasses 7. Thus, inner and outer shoulders 14 and 15 are provided in the lower rail 2. The lower glasses 7 rest on the shoulder 15. One side of the channel members 10 in the lower rail 2 rests on the shoulder 14.

The upper mullion 6 includes substantially V-shaped ends 16 which accommodate the oppositely beveled edges 8 of the upper rail 1 and the transom 4. Tongues 17 project from the ends of the mullion 6 for engagement in the grooves 9 of the upper rail 1 and the transom 4. The removable transom 4 comprises ends of a similar construction to those of the mullion 6 for engagement with the side rails 3.

The lower mullion 5 is first constructed in a manner similar to the upper mullion 6 and then split longitudinally from one end to a point adjacent its other end, as at 18. When the lower mullion 5 is to be installed, the separation of the two halves is completed in a manner to provide complementary inner and outer sections 19 and 20, respectively, which are detachably secured together with the lower glasses 7 therebetween through the medium of a screw 21 or other suitable means. Longitudinal splitting of the lower mullion 5 provides opposed ribs 22 on the sections 19 and 20. Tongues 23 are provided on the upper ends of the mullion sections 19 and 20, said tongues constituting continuations of the ribs 22. It will be observed that no tongues are provided on the lower ends of the lower mullion sections 19 and 20.

The device may be assembled substantially as follows:

The mullion 6 is engaged with the upper rail 1 and the upper glasses 7 are slipped upwardly between said mullion 6 and the side rails 3. Of course, the grooves 9 in the members 3, 6 and 1 accommodate the marginal portions of the upper

glasses 7. The transom 4 is then mounted between the side rails 3 and engaged with the lower end of the upper mullion 6, the grooves 9 in said transom receiving the lower edges of the upper glasses 7. The resilient glass retaining channel members 10 are inserted in the grooves in the upper rail 1 and the transom 4, and then in the grooves in the side rails 3. The outer section 20 of the lower mullion 5 is then positioned between the transom 4 and the lower rail 2 with the tongue 23 on the upper end of said section 20 engaged in the lower groove 9 in said transom 4. The lower ends of the lower glasses 7 are then engaged in the well 13 and said lower glasses are then moved toward the side rails 3 for engagement in the grooves 9 therein. This also positions the lower glasses 7 on opposite sides of the rib 22 of the mullion section 20. The upper ends of the lower glasses 7 are then swung into alignment with the groove 9 in the lower edge of the transom 4. The lower glasses 7 may now be elevated and brought to rest on the shoulder 15. The tongue 23 on the upper end of the mullion section 19 is then engaged in the groove 9 in the lower edge of the transom 4 and the lower end of said section 19 is secured through the medium of the screw 21 to the section 20. The resilient channel members 10 are then inserted in the grooves 9 of the transom 4 and the bottom rail 2, and then in the side rails 3. Should it be desired to remove the glasses 7, the foregoing operation is substantially reversed. The rails 1, 2 and 3 may be firmly secured together in any suitable manner.

In the modification illustrated in Figure 7 of the drawings, a sliding lower sash is indicated at 30. The members or rails comprising the sash 30 are provided with beads 31 on their inner edges for engagement with a glass 32. Retaining strips 33 for the glass 32 are provided in the sash 30 for coaction with the beads 31. The strips 33 are provided, on their inner edges, with resilient flanges 34 of angular cross-section for engagement with the glass 32, said flanges being provided, on their free longitudinal edges, with beads or the like 35.

It is believed that the many advantages of a window sash constructed in accordance with the

present invention will be readily understood, and although preferred embodiments are as illustrated and described, it is to be understood that further modifications and changes in the details of construction may be resorted to which will fall within the scope of the invention as claimed.

What is claimed is:

A window sash comprising a frame including spaced vertical side rails, a horizontal rail permanently connecting the side rails, a horizontal transom extending between the side rails in spaced parallel relation to the horizontal rail, a mullion extending between the horizontal rail and the transom intermediate the side rails, said rails, transom and mullion all having similar communicating grooves formed in the corresponding edges thereof for reception of the margins of two panes of glass, said grooves being of similar depth at both sides thereof and being wider than the thickness of the panes of glass, removable strip members fitted in said grooves to secure the panes of glass in position contacting a side wall of each groove, said mullion embodying complementary longitudinal inner and outer half-sections having tongues on corresponding ends thereof fitting in the groove of the transom, the other ends of said half-sections being free of tongues, and means separably securing said half-sections together, the horizontal rail having its groove provided with a narrow central bottom extension forming a well for reception of the adjacent marginal portions of the panes of glass when the strip members are removed, and shoulders at opposite sides of the well at the top of the latter respectively for engagement by the adjacent edges of the panes of glass and the adjacent strip members, said well being of a depth to permit disengagement of the panes of glass from the groove of the transom so that they may be removed upon separation and removal of the mullion sections and movement of the panes of glass toward each other to disengage them from the grooves of the side rails and further subsequent movement of the same to disengage them from the well and the associated groove of the horizontal rail.

HEROLD H. HEBESTREIT.
